US00D747336S

(12) **United States Design Patent**
Carrigan et al.

(10) **Patent No.:** **US D747,336 S**
(45) **Date of Patent:** **** Jan. 12, 2016**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Taylor Gerard Carrigan**, San Francisco, CA (US); **Jeffrey Ma**, Emerald Hills, CA (US); **Jeffrey L. Robbin**, Los Altos, CA (US); **Jim Young**, Livermore, CA (US)

(73) Assignee: **Apple Inc.**, Cupertino, CA (US)

(**) Term: **14 Years**

(21) Appl. No.: **29/507,923**

(22) Filed: **Oct. 31, 2014**

Related U.S. Application Data

(63) Continuation of application No. 29/415,033, filed on Mar. 6, 2012, now Pat. No. Des. 716,825.

(57) **CLAIM**

The ornamental design for a display screen or portion thereof with graphical user interface, as shown and described.

DESCRIPTION

The FIGURE is a front view of a display screen or portion thereof with graphical user interface showing our new design; The outermost broken lines in the FIGURE show a display screen or portion thereof, and form no part of the claimed design. The other broken lines in the FIGURE and the area within those broken lines show portions of the graphical user interface that form no part of the claimed design.
